UNITED STATES PATENT OFFICE

2,602,455

TOBACCO PIPE CLEANER

Emily Berner, New York, N. Y.

Application August 13, 1946, Serial No. 690,171

1 Claim. (Cl. 131—246)

2

It is well known by persons who smoke a tobacco pipe that the bowl of the pipe becomes incrusted with a lining of carbon, and in order to maintain a pipe properly, it should be regularly cleaned of the incrusted.

Known devices for cleaning the bowls of tobacco pipes are inadequate for properly doing the work, principally because of their non-threaded cross-section, because of which they undercut the incrusted in the pipe and damage the bowl.

An object of this invention is to provide a tobacco pipe cleaner so constructed that peripheral portions of the cutter head taken on a section at right angles to the vertical axis of the cleaner lie in a circle and have thread elements thereon which follow the orbit of a continuous thread in order to make a thread-like cut, in cleaning the bowl of the pipe, thus avoiding undercutting the incrusted and damaging the pipe bowl.

Another object of this invention is to provide a tobacco pipe cleaner comprising two identical members which are integral solely at the upper portion of the device, the members being spaced apart from each other at the central portion of the device whereby the lower portions of the members have a degree of resiliency in a lateral direction to allow relative movement of the members toward each other to yieldingly engage and scrape the walls of the pipe without under-cutting the incrusted.

Another object of this invention is to provide each member with a laterally extending projection at its lower end and with a guideway adapted to receive the projection of a coating member for interengaging the members at their lower ends in slideable relation and retaining the members in their normal cutting positions.

With the above and other objects in view, the invention will be hereinafter more particularly described, and the combination and arrangement of parts will be shown in the accompanying drawings and pointed out in the claim which forms part of this application.

Reference will now be had to the drawings, wherein like numerals of reference designate corresponding parts throughout the several views, in which:

Figure 1 is a perspective view of a tobacco pipe showing the pipe cleaning implement in operating position therein.

Figure 2 is a side elevation of the implement shown in Figure 1.

Figure 3 is a top plan view of the implement.

Figure 4 is a cross-sectional view, the section being taken as on line 4—4 in Figure 2.

Figure 5 is a cross-sectional view, the section being taken as on line 5—5 in Figure 3 but showing only one projection in elevation.

Figure 6 is a side view of the implement looking in a direction endwise of the handle.

Figure 7 is a cross-sectional view taken on line 7—7 in Figure 2, and drawn on an enlarged scale.

In the illustrated embodiment of the invention, the numeral 10 indicates my improved tobacco pipe cleaner comprising a cutter head 11 having a rounded lower edge 12 and generally having a contour suitable to fit a pipe bowl 13 of a tobacco pipe 14.

Portions of the outer surface of the cutter head 11 are threaded or notched, the thread elements 15 extending from a stem portion 16 adjacent a handle 17 to the rounded lower edge 12. The thread elements 15 follow the orbit of a continuous thread. The cutter head 11 has a longitudinally disposed linear opening 19 which divides the cutter head into two members each having two cutting sections 20.

The cutter head 11 has substantially parallel sides or parallel cutting edges, the thread elements 15 extending a considerable depth into the sides. Extending from the upper end of the cutter head 11 is the handle 17 which is, in a lengthwise direction, larger than the diameter of the cutter head.

The tobacco pipe cleaner 10 is preferably stamped from sheet metal. The cutter head 11 may be inserted into the bowl 13 of the pipe 14 and the pipe cleaner turned in a right-hand direction to remove the cake or lining of carbon which accumulates in a pipe. The thread elements 15 undercut the layer of carbon but obviate the possibility of cutting or otherwise damaging the pipe.

As best shown in Figures 6 and 7, the cutter head 11 comprises two identical members 22, 22. The stem portions 16 and the handle portions 17 are in practice in abutting relation and integrally united such as by welding. The opening 19 extends from the stems 16 all the way down to the lower end of the device.

It is to be noted that, due to the spaced-apart relation of the lower end portions of the members 22, that the lower portions of the said members are resilient in a lateral direction at the lower end of the device to allow relative movement of the members toward each other to yieldingly engage and scrape the walls of the pipe bowl without under-cutting the incrusted in the pipe.

Each member 22 has a laterally extending pro-

jection or key 23 of rectangular cross-section which is stamped therefrom. Each member 22 has a guideway or keyway 24 adapted to receive the projection or key 23 of the other member to permit slidable interengagement between the two members 22 at their lower ends.

It is to be noted that a keyway 24 of rectangular cross-section is formed when a key 23 is stamped out from the cutting sections 20 of a member 22. As best shown in Figure 6, the key 23 of one section is in close interengagement with the keyway 24 of the other section during the relative movement of the cutting sections toward each other.

It is also to be noted that in each cutting section 20 all the thread elements 15 lie in a single straight line. As best shown in Figures 5 and 6, it will be seen that each thread element 15 is shaped in the form of a square thread, well known in the art.

In accordance with the patent statutes I have described and illustrated the preferred embodiment of my invention, but it will be understood that various changes and modifications can be made therein without departing from the spirit of the invention as defined by the appended claim.

I claim:

In a tobacco pipe cleaning implement, a two-member cutter head comprising four cutting sections having their outer edges lying in a circle, each section having outwardly extending right-angled thread cutting elements, the thread cutting elements in said cutting sections being arranged to follow the orbit of a continuous circular thread, all the thread elements in each cutting section lying in a straight line, the outer edges of said four cutting sections being adapted to enter into a tobacco pipe bowl for cutting incrustations therein at a plurality of points along

the circumference of the bowl with a thread-like cut simultaneously, said sections being fixedly connected in abutting relation solely at the upper end portion of said implement, said members being relatively movable at the lower end portion of said implement, each of said members having a key stamped therefrom but attached thereto, each member having a close fitting keyway for the key of the other member for permitting slid-
10 able interengagement between said members at their lower ends at the lower portions of said threaded portions, each key stamped from a member providing the keyway in said member, said implement having a convex rounded lower portion below said threaded portion of a contour suitable to fit a pipe bowl, said members being resilient in a lateral direction at their lower ends to allow relative movement of said cutting sections toward each other to yieldingly engage and
15 20 scrape the walls of the pipe bowl without under-cutting said incrustations.

EMILY BERNER.
